ATTORNEY

UNITED STATES PATENT OFFICE.

OSCAR GROSSMANN, OF NEW YORK, N. Y.

WINDOW CLEANER.

Application filed April 4, 1927. Serial No. 180,860.

This invention relates to the class of window cleaning devices, and has especial reference to that class of devices which may be used from the inside of a window for 5 cleaning the outside surfaces thereof.

The principal object of the present invention is the provision of a device of the indicated character which embodies novel features of construction and which functions 10 in a novel manner for obtaining the results looked for, which are obtained with the desired effect, easily and quickly.

Another object of the invention is the provision of a device of the indicated character 15 which will be simple of construction and comparatively inexpensive.

The nature of the invention and its distinguishing features and advantages will appear when the following specification is 20 read in connection with the accompanying drawing—

Figure 1 is a view through a window construction and illustrating the device of the present invention in use.

Fig. 2 is a sectional elevation of the device.

Fig. 3 is a perspective view illustrating the manner of assembling one cleaning element with another.

Referring now more particularly to the several views of the drawing, it will be apparent that, the device, generally stated, comprises a guiding means 10 in the form of a tube, preferably of metal and one which 35 will have the necessary rigidity, a cleaning element 11, and a manipulating means 12 adapted to be guided for reciprocating movement by the tube 10 for carrying out the cleaning operations. The tube 10 consists of a straight section 13, and a curved section 14. The manipulating means 12, 40 may be diversely formulated, and in the present instance, consists of a metal rod 15 having connected therewith a flexible element 16. The flexible element 16 in the present instance consists of a closely coiled wire. The free end of the element 16 has a knob 17 to prevent the hand from slipping off of the end portion of the element 45 while manipulating the same. The upper end of the rod 15 has connected therewith

the cleaning element 11 which is in the form of a squeegee which consists of a holder member 18 connected with the rod 15, and a strip of rubber 19 secured to the member 55 18. The holder member 18 carries suitable elastic bands 20 or the like. The said bands 20 serve for detachably holding a second cleaning element such as the sponge 21. The sponge or its equivalent serves for 60 applying water to the windowpanes whereas, the squeegee serves for removing the water applied to the windowpane and the particles of dust which will be carried thereby.

In the use of the device, it is only necessary to raise the window sash slightly. A person on the inside of the room may hold the tube 10 in one hand with that section 13 thereof disposed at the outside and the section 14 extending to the inside then by imparting to the element 16 a reciprocating motion, a similar motion will be imparted to the cleaning element 11. The cleaning element 11 is designed so as to be passed 70 between the lower rail of a top window sash and the windowpane of the lower sash, as shown most clearly in Fig. 1.

I claim:

1. A window cleaner comprising a guide 80 tube, a cleaning element, means adapted to be guided for sliding movement in the guide tube, said means consisting of an inflexible rod connected with the cleaning element, and a flexible manipulating portion connected with the rod, the rod projecting beyond one end of the tube with the flexible manipulating portion projecting beyond the other end of the tube.

2. A window cleaner comprising a curved 90 guide tube, a cleaning element, means adapted to be guided for sliding movement in the guide tube for causing the sliding movement of the cleaning element, said means consisting of an inflexible rod connected 95 with the cleaning element, and a flexible manipulating portion connected with the rod, the rod projecting beyond one end of the tube with the flexible manipulating portion projecting beyond the other end of the 100 tube.

OSCAR GROSSMANN,
